UNITED STATES PATENT OFFICE.

LOUIS SCHWARTZBERG, OF CHICAGO, ILLINOIS.

CUSHION FOR EGG CASES.

Application filed June 27, 1921. Serial No. 480,501.

To all whom it may concern:

Be it known that I, LOUIS SCHWARTZBERG, a citizen of the United States, residing at Chicago, in the county of Cook and State 5 of Illinois, have invented a new and useful Improvement in a Cushion for Egg Cases, of which the following is a specification.

My invention relates to packing and storing receptacle boxes, and the like, and more 10 particularly to a cushioning device to be placed in the bottom, top or other convenient place in the container in order to permit of a cushioning of the articles packed therein. Another object of my present invention is the provision in a cushioning device of a structure that will permit of the 15 circulation of air below the same and for the purpose of ventilating the receptacle and permitting circulation of air about the 20 articles contained in the receptacle.

This present device is capable of employment in connection with boxes of candy, egg cases, and, in fact, any type of container or receptacle adapted to receive and 25 store articles in a cellular structure. In egg cases, as is well known, as well as in types of candy boxes and boxes for ornaments, it is the practice to employ a plurality of parallel longitudinal and transverse walls 30 that intersect to form cells or spaces into which the articles are deposited and are separated from each other. Usually the articles upon the bottom and top tiers of the receptacle or box are subject to little or no 35 cushioning, and in the case of egg crates the weight of the eggs above the bottom tier frequently causes the eggs in said tier to receive damaging impact when in transit so that they become broken. Also in the packing 40 of eggs for cold storage there is little or no ventilation in the top and bottom rows of the crate and the eggs become musty due to moisture and poor circulation of air. With my present invention, I am able to overcome 45 the defective ventilation and circulation of air, and am also able to provide a dependable cushion that prevents articles in the top or bottom tiers becoming broken through impact or jar.

I prefer to accomplish the divers objects of my invention in substantially the manner hereinafter described, and as more particularly pointed out in the claims.

In the drawings:

Figure 1 is a plan view of the bottom of 55 my improved cushioning device with a flat or the covering element thereof removed.

Figure 2 is a top plan of a fragmentary portion of the cushioning device with the top 60 flat broken away.

Figure 3 is an edge view of a fragmentary portion showing my cushioning device in the bottom of an egg crate adjacent the corner and the cells shown fragmentary.

Figure 4 is a sectional view on line 4—4, 65 Figure 1, looking in the direction of the arrows.

Figure 5 is a sectional view on line 5—5, 70 Figure 1, looking in the direction of the arrows.

Figure 6 is a sectional view on line 6—6, 75 Figure 1, looking in the direction of the arrows.

Figure 7 is a fragmentary corner view of the bottom of a modified structure, with the 80 flat removed.

For the purpose of convenience, I have illustrated and described my invention as applied to egg cases or crates, but it will be understood that the principles are adapted 85 for use in connection with any type of cellular or similar receptacles or storage vessels.

Referring more particularly to Figure 1, it will be observed my improved cushion preferably comprises a rectangular plate 10 85 formed of a sheet of strawboard, cork, wood, or any other suitable material, that is substantially flat upon its upper surface, as seen in Figures 3 to 6, inclusive, is provided with a plurality of large recesses or apertures 11, and intermediate these large recesses or openings are smaller apertures 12 that extend entirely through the structure. The recesses or apertures 11 are arranged, as 90 seen in the drawings, in six rows with six in each row for an egg case, and are slightly smaller in diameter than the diameter of an egg, and the edges of recesses or apertures 11 upon the upper face of the structure are countersunk, as at 13, (Fig. 2) so as to avoid 95 presenting a sharp corner to the article contained in the receptacle. If desired, of course, the countersinking or beveling of the edge may be dispensed with. When apertures are formed, the material between the 100 same provide feet 14 upon the bottom of

the plate, and the space surrounding the small apertures 12 is cut away, about two-thirds the thickness of the material, to provide channels 15 that divide the feet from each other in each direction. Concaved portions 16 are provided in the edges of the structure to facilitate the removal of the cushion, and widened channels 17 divide the feet which are provided along the longitudinal and transverse edges of the structure. Channels 15 and 17 afford continuous passageways for air to circulate throughout the under portion of the cushion and the corners of the cushion are provided with substantially square feet or projections 18.

When the cushion has been placed with the feet down in a section of an egg crate, the ordinary flat 19, which is usually of three-ply fibre board, is placed upon the top of element or plate 10, after which the cellular sections 20 are superimposed thereon with a dividing flat 19 between each cell section. The bottom layer or tier of eggs in the case rests upon the lowermost flat 19 and are positioned above the respective recesses or large apertures 11 in the cushion structure so that the bottom tier of eggs will be afforded a slight cushion and prevented from breaking.

The structure heretofore described may be modified by making the recesses or large openings angular instead of circular, in which event the appearance of the bottom of the structure will be as seen in Figure 7, in which the recesses or openings 11^a are octagonal and the feet 14^a are rectangular in outline, while the cutout portions 16^a in the edges are likewise rectangular instead of segmental in shape. In the modified structure just described the intermediate smaller apertures 12^a are made round, as in the preceding figures. The structure in Figure 7 may be found to be more desirable in some instances for the reason that the air passageways 15^a or channels between the feet and below the top are somewhat wider and of greater area than in the preferred form, shown in Figure 1. The manner of using the structure shown in Figure 7 is the same as that described in the preferred form, and it will be understood that further modifications are possible without departing from the principles I have disclosed.

What I claim is:—

1. A cushion for cellular packing receptacles comprising a substantially flat plate,

and elongated feet extended longitudinally and transversely upon the bottom of said plate.

2. A cushion for cellular packing receptacles comprising a substantially flat plate having a plurality of recesses therein, and feet positioned longitudinally and transversely upon the bottom of said plate between the recesses. 60

3. A cushion for cellular packing receptacles comprising a substantially stiff plate supported upon and spaced a slight distance from the bottom of the receptacle, said plate provided with a plurality of recesses, and a yielding flat coacting with one face of said plate whereby said flat may be depressed at the locations of said recesses. 70

4. In an egg-crate, a plurality of cell-sections, flats interposed between said sections, and a cushion structure consisting of a substantially rigid element having a plurality of supporting feet; said element having recesses between said feet and registering with the cells in said sections, and a flat positioned between said element and the adjacent cell section. 75

5. In an egg-crate a plurality of cell-sections, flats interposed between said sections, and a cushion structure consisting of a substantially rigid element, a plurality of longitudinally and transversely disposed feet extending downwardly from the bottom of said element to support the latter above the bottom of the crate, said element provided with a plurality of apertures disposed between the longitudinal sides of said feet, and a flat positioned between said element and the adjacent cell-section. 85

6. A cushion for cellular packing receptacles comprising a suitable plate, and a plurality of longitudinally and transversely arranged projections upon the bottom of said plate; said projections being spaced from each other whereby air passageways are provided below said plate. 95

7. A cushion for cellular packing receptacles comprising a substantially flat plate, and elongated feet disposed in spaced relation to each other and in intersecting rows, whereby ventilating passageways are provided in a plurality of directions. 105

Signed at Chicago, county of Cook and State of Illinois, this 21st day of June, 1921.

LOUIS SCHWARTZBERG.
